FREQUENCY MODULATION RECEIVING
SYSTEMMurray G. Crosby, Riverhead, N. Y., assignor to
Radio Corporation of America, a corporation
of Delaware

Application June 4, 1943, Serial No. 489,627

6 Claims. (Cl. 250—20)

1

My present invention relates to receivers of frequency modulated carrier waves, and more particularly to a novel method of, and means for, detecting frequency modulation waves.

An important object of this invention is to provide a method of detecting frequency modulated carrier wave energy in an entirely unconventional manner, and without employing any of the usual forms of discriminator circuits; according to my invention the usual discriminator network having an S-shaped detection characteristic is dispensed with.

Another object of this invention is to provide a novel method of receiving frequency modulated, or phase modulated, carrier waves wherein the superheterodyne method of reception is employed; the normal local oscillations are frequency modulated by a superaudible frequency oscillator; the originally received modulated waves are ultimately translated into amplitude modulated waves whose carrier is of the aforesaid superaudible frequency and whose modulation components are those of the originally collected frequency modulated carrier wave, such amplitude modulated energy being then detected in the conventional manner.

The novel features which I believe to be characteristic of my invention are set forth with particularity in the appended claims; the invention itself, however, as to both its organization and method of operation will best be understood by reference to the following description, taken in connection with the drawing, in which I have indicated diagrammatically a circuit organization whereby my invention may be carried into effect.

In the drawing:

Fig. 1 shows a receiving system constructed in accordance with my invention.

Fig. 2 graphically illustrates the characteristic of the detector input circuit 8.

Fig. 3 depicts the wave form of the output energy of detector 9.

Fig. 4 represents the wave form of the amplitude modulated energy at the combiner output circuit.

It is to be clearly understood that the system shown by me in Fig. 1 is purely illustrative, and is in no way restricting on the scope of my generic concept. As stated heretofore, the system shown in Fig. 1 is equally capable of receiving frequency modulated or phase modulated carrier wave energy or even hybrids thereof. The generic term "angle modulated" whenever used hereinafter is to be understood as including any of these forms of modulation. For the sake of brevity the design-

2

nation "FM" will be hereinafter employed when referring to frequency modulated carrier waves. Wherever used, the designation "AM" designates amplitude modulated carrier wave energy. For the purposes of the present specific illustration it is assumed that the signal collector 4 has applied to it FM wave energy. The center, or midband, frequency of the collected energy may be in any of the assigned FM bands, as, for example, the presently assigned 42-50 megacycle (mc.) FM band.

The numeral 2 denotes the usual radio frequency amplifier which may comprise one or more stages of tunable radio frequency amplification. The converter tube 3 is of the well known pentagrid converter type, and has applied to its input grid 4 the selected, amplified FM wave energy. The tunable local oscillation circuit 5 has the oscillation grid 6 connected to the high potential side thereof. The cathode of the converter tube is connected to a tap on the oscillation coil 7 thereby to provide a Hartley form of oscillator circuit. Of course, the tank circuit 5 will be tuned to a frequency such that it beats with the midband frequency of the selected FM waves to produce in the resonant output circuit 8 of the converter tube intermediate frequency (I. F.) energy whose center frequency is of the predetermined operating I. F. value.

In other words, the received FM energy has had its center frequency (F_c) reduced to the operating I. F. value without any change in the frequency deviations of the signal energy. These frequency deviations may be of a relatively small ratio, or they may be of a large ratio. The circuit 8 is given a substantially single-peak resonance curve, the center frequency (F_c) being located at the peak of the resonance curve. Attention is directed to Fig. 2 which shows an idealized characteristic of the resonant circuit 8. The circuit 8 functions as the input circuit of a detector tube shown as a diode rectifier 9. The anode 10 of rectifier 9 is coupled to the high potential side of input circuit 8 through coupling condenser 11. The cathode of rectifier 9 is grounded. The resistor 12 connects the anode and cathode of the diode 9. In other words the resistor 12 acts as the rectifier load resistor, and circuit 8 is a selective input circuit for the detector 9.

According to my invention the oscillatory energy existing in the local oscillation circuit 5 is frequency modulated in accordance with the oscillatory output of a superaudible frequency oscillator designated by numeral 13. Essentially, this superaudible frequency oscillator will provide

oscillations of substantially constant amplitude and constant frequency. For example, the superaudible frequency may be of the order of 20 kilocycles (kc.), and any desired form of superaudible frequency oscillator may be used. I have shown the specific form of superaudible frequency oscillator which has been disclosed, and claimed, by me in my U. S. Patent No. 2,269,417, granted January 6, 1942. The superaudible frequency oscillator shown in the present case may be analogous, for example, to that shown in Fig. 1 of my said patent.

It can be stated that, in general, the oscillator comprises a pair of triode electron sections which are enclosed in the same tube envelope. A common cathode resistance 14 is utilized for the cathodes of the two triode sections. Hence, the voltage which is applied to grid 15 is fed to the cathode circuit of the opposite triode section. Utilizing the cathode circuit of section T₁ as an output circuit results in 100% inverse feedback, and the voltage applied to the grid 15 of section T₁ appears unamplified on its cathode. Due to this high degree of inverse feedback the grid 15 of section T₁ may be swung over a wide range of voltage without drawing grid current. Therefore, the impedance presented to the tuned circuit 16 by the grid is that of a negatively biased, or class A, grid which is very high. In order to produce sustained oscillations the feedback voltage at tuned circuit 16 is fed to the grid 15 through blocking condenser 17.

This feedback voltage must be fed back to the grid 18 of the second section T₂ with a 180 degree phase reversal in order to produce oscillations. This is readily accomplished due to the fact that the common cathode resistance 14 effects such reversal. A positive voltage on the grid 15 causes more current to flow through the cathode resistor 14 and thereby makes both cathodes more positive. The cathode of section T₂ becoming more positive is equivalent to grid 18 becoming more negative. Thus, a positive voltage change on the grid 15 is equivalent to a negative voltage change on grid 18, and the required 180 degree phase reversal is obtained. The tuned circuit 16 is resonated, in this particular case, to the required frequency of oscillation, which has been chosen as 20 kc. The oscillations are taken from the slide tap 19 of potentiometer 20, and the amplitude of the oscillatory output is thus regulated. These oscillations are employed to frequency modulate the local oscillations produced at tank circuit 5. The frequency modulated local oscillations heterodyne with the incoming signal energy in converter 3 to produce frequency modulated I. F. energy in tuned circuit 8.

Considering, first, the manner in which the superaudible frequency oscillations are utilized to frequency modulate the oscillations developed in tank circuit 5 of the converter tube 3, a reactance tube 21 is used for this purpose. The latter is shown specifically as of the pentode type, any other type of tube may be used. The plate 22 thereof is coupled to the high potential side of oscillation circuit 5 through a direct current blocking condenser 23. The positive voltage is supplied to the plate 22 through a radio frequency choke coil 24. The cathode of tube 21 is connected to ground through a grid biasing resistor 25. Alternating voltage at plate 22 is applied to the input grid 26 of tube 21 in phase quadrature relation. To secure this phase quadrature relation there is employed a phase shifter network which consists of a condenser 27 ar-

ranged in series with resistor 28. The upper end of condenser 27 is connected to the plate 22, while the grid 26 is connected to the junction of condenser 27 and resistor 28. The lower end of resistor 28 is bypassed to ground for radio frequency current by condenser 28'. The lower end of resistor 28 is connected by lead 29 to the adjustable tap 19 of potentiometer 20.

As is well known to those skilled in the art, if the reactance of condenser 27 is relatively large with respect to the resistance of resistor 28, there will be provided across tank circuit 5 an apparent condensive effect whose magnitude will be a function of the gain of tube 21. In other words, the plate to cathode impedance of tube 21 simulates a condenser across oscillation circuit 5 by virtue of the phase quadrature voltage applied to grid 26. The gain of tube 21 depends on the voltage of grid 26. The voltage of grid 26 in turn depends upon the varying magnitude of the periodic voltage derived from the superaudible frequency oscillator. The grid 26 has a normal bias determined by the voltage across cathode resistor 25, since the grid 26 returns to ground through potentiometer 20. It will now be seen that the local oscillation frequency is actually deviated back and forth with respect to a selected local oscillation frequency value in dependence upon the 20 kilocycle oscillations.

Returning, now, to the detector 9 there is developed across resistor 12 a voltage whose idealized wave form has been represented in Fig. 3. The anode 10 of rectifier 9 is connected to ground through a parallel resonant circuit 30 which is tuned to the superaudible frequency (specifically 20 kc.). The high potential side of circuit 30 is connected by filter resistor 31 to the anode 10. By virtue of this network 30 there is developed thereacross the wave form shown in Fig. 3, and it will be noticed that at each half cycle of the wave form there occurs a polarity reversal. Actually, the modulated energy appearing across circuit 30 is carrier-eliminated modulation.

The process of producing this carrier-eliminated modulation is as follows: The intermediate frequency energy appearing in tuned circuit 8 is modulated by two frequency modulations. The normal desired modulation of the incoming signal is present, and, in addition, the superimposed sub-carrier which modulates at a superaudible rate. In the unmodulated condition of the incoming signal the intermediate frequency energy in tuned circuit 8 assumes the frequency F_c shown in Fig. 2. In this condition the superaudible frequency sub-carrier varies the frequency over the round top of the selectivity curve in a manner which does not produce amplitude modulation having a fundamental component. Second harmonic amplitude modulation will be produced, but will be rejected by tuned circuit 30 in the output of detector 9. Consider, now, in Fig. 2 that the incoming signal is deviated in accordance with the modulation so that the intermediate frequency energy in circuit 8 is shifted to the frequency F₁. The superaudible frequency modulation now varies the intermediate frequency energy over the range between F₂ and F₃. This varies the amplitude between points *a* and *b* so as to produce an amplitude modulated output of the fundamental 20 kc. wave.

When the frequency is deviated in the opposite direction by the incoming signal, for instance to the frequency F₄, the sub-carrier modulation varies the amplitude of the fundamental 20 kc.

wave in the same manner but in opposite sense, since the signal is tuned to the opposite side of the resonance curve. The result of this dual modulation in tuned circuit 38 is an amplitude modulated wave which, when detected, produces the wave form as shown in Fig. 3. I have termed a wave form of the type shown in Fig. 3 "carrier-eliminated modulation." The amplitude modulation of this wave is detected by detector 49, and its fundamental component is selected by filter 31-30. The signal energy at circuit 30, as shown in Fig. 3, consists of the superaudible frequency (20 kc.) which is varying in amplitude and phase in accordance with the frequency swings of the FM waves received at collector 4. Further, a polarity reversal of the modulated superaudible frequency occurs as the received signal passes through Fe. To demodulate this form of wave, it is combined with a wave of the same superaudible frequency whose phase is fixed. In other words, there is applied through phase adjuster 37, 38 to grid 36 of combiner tube 33 a reference wave of 20 kc. whose phase and amplitude are constant. Hence, the phase and amplitude variations at grid 32 will add or subtract from the fixed phase and amplitude at grid 36 to provide a resultant 20-kc. wave which is amplitude modulated in accordance with the frequency swings of the FM signals at collector 4. The resulting output of tube 33 is an amplitude modulated wave composed of carrier and side bands which produces a wave form as shown in Fig. 4. This wave form is detected in detector 45 to produce the desired modulation which was present on the original incoming FM signal.

The energy at the output of circuit 30 is transmitted to the intermediate control grid 32 of combiner tube 33. Grid 32 is coupled to the high potential side of tuned circuit 30 through a coupling condenser 34. The grid 32 is returned to ground by resistor 35. The combiner tube is shown as being of the pentagrid type, but it is to be understood that any other type of tube may be utilized. The function of the combiner tube is to combine the carrier-eliminated modulation with the original superaudible frequency oscillations. This is done by connecting the first grid 36 to the resistor 37 of a phase adjuster network. The resistor 37 has one end thereof grounded, while its upper end is connected by adjustable condenser 38 to the condenser 11 of the superaudible frequency oscillator network. The adjustable slider 39 selects from the phase adjuster resistor 37 the desired magnitude and phase of superaudible frequency oscillatory voltage. The phase of combination is selected by adjusting condenser 38 of the phase adjuster 38-37.

The resultant amplitude modulated signal voltage is developed in the resonant output circuit 40 connected to the plate 41 of the combiner tube 33. The circuit 40 is tuned to the superaudible oscillation frequency of 20 kc. The detector is represented by diode rectifier 45 whose tuned input circuit 42 is resonated to the superaudible carrier frequency. The rectifier input circuit 42 is reactively coupled to combiner tube output circuit 40. Across the output load resistor 43, which is by-passed by condenser 44 for superaudible frequency currents, there are developed the modulation signals which may be amplified in any desired manner.

While I have indicated and described a system for carrying my invention into effect, it will be apparent to one skilled in the art that my invention is by no means limited to the particular

organization shown and described, but that many modifications may be made without departing from the scope of my invention, as set forth in the appended claims.

What I claim is:

1. In a receiver of angle modulated carrier waves, a converter having input and output circuits, means applying said waves to the converter input circuit, a local oscillator applying high frequency waves to the converter to provide beat frequency waves in the converter output circuit, said output circuit being tuned to a predetermined beat frequency and having a resonance curve peaked at said predetermined frequency, means for varying the oscillator waves at a superaudible frequency, detection means coupled to said converter output circuit to produce waves of said superaudible frequency varying in phase and amplitude in accordance with the angle modulation of the aforesaid carrier waves, and means to combine said variable phase and amplitude waves with waves of the same superaudible frequency and fixed phase to produce resultant waves of said superaudible frequency and amplitude modulated in accordance with said angle modulation.
2. In a receiver of angle modulated carrier waves, a converter having input and output circuits, means for applying received waves to the converter input circuit, means for applying high frequency waves to the converter to provide beat frequency waves in the converter output circuit, said output circuit being sharply tuned to a predetermined beat frequency and having a frequency response curve peaked at said predetermined frequency, means for varying the high frequency waves at a superaudible frequency, detection means coupled to said converter output circuit to produce waves of said superaudible frequency and varying in phase and amplitude in accordance with the angle modulation of the aforesaid carrier waves, means to combine waves of variable phase and amplitude with waves of the same superaudible frequency and fixed phase to produce resultant waves of said superaudible frequency and amplitude modulated in accordance with said angle modulation, and means for rectifying the resultant amplitude modulated waves.
3. The method which includes receiving angle modulated waves, locally producing superaudible frequency waves, concurrently reversing the phase and varying the amplitude of superaudible frequency wave energy derived from said locally produced waves in accordance with the angle modulation of said received waves, combining said superaudible wave energy of reversed phase and variable amplitude with waves of constant amplitude and phase of said superaudible frequency to produce resultant amplitude modulated waves of said superaudible frequency, and detecting the resultant waves to produce modulation signals representative of said angle modulation.
4. In a receiver of frequency modulated carrier waves, a converter having input and output circuits, means applying received waves to the converter input circuit, a local oscillator applying high frequency waves to the converter to provide beat frequency waves in the converter output circuit, said output circuit being tuned to a predetermined beat frequency and having a resonance curve peaked at said predetermined frequency, means for varying the oscillator waves at a superaudible frequency, detection means

coupled to said converter output circuit to produce waves of said superaudible frequency reversible in phase and variable in amplitude in accordance with the frequency modulation of the aforesaid carrier waves, means to combine 5 said reversible phase and variable amplitude waves with waves of the same superaudible frequency and constant phase and amplitude to produce resultant waves of said superaudible frequency and amplitude modulated in accordance 10 with said frequency modulation, and means for detecting the resultant waves.

5. In a receiver of angle modulated carrier waves, a converter having input and output circuits, means applying received waves to the converter input circuit, a local oscillator applying high frequency waves to the converter to provide beat frequency waves in the converter output circuit, said output circuit being tuned to a predetermined beat frequency and having a 20 resonance curve peaked at said predetermined frequency, means for varying the oscillator waves at a superaudible frequency substantially less than the carrier frequency, a diode rectifier coupled to said converter output circuit to produce 25 waves of said superaudible frequency reversible in phase and variable in amplitude in accordance with the angle modulation of the aforesaid carrier waves, a selective filter coupled to the rectifier tuned to said superaudible frequency, means to combine said reversible phase and variable amplitude waves with waves of the same superaudible frequency and constant phase 30

and amplitude to produce resultant waves of said superaudible frequency and amplitude modulated in accordance with said angle modulation, and a rectifier coupled to said combining means.

6. In combination, a source of high frequency waves of variable frequency, a second source of superaudible frequency waves of constant amplitude and constant frequency, means responsive to the superaudible waves for angle modulating said high frequency waves, a detector provided with a resonant input circuit having a frequency response characteristic peaked at the center frequency of said variable frequency waves, means applying said angle modulated high frequency waves to said resonant circuit thereby to produce at the detector output variable amplitude waves of said superaudible frequency reversible in phase as said angle modulated variable frequency waves pass through said center frequency value, means for combining said detector output waves with waves from said second source to produce resultant amplitude modulated waves of said superaudible frequency, and means utilizing the resultant waves.
